UNITED STATES PATENT OFFICE.

LEONARD L. BASSETT, OF SIOUX FALLS, SOUTH DAKOTA.

WHEEL PULLER.

Application filed May 17, 1923, Serial No. 639,624. Renewed January 23, 1925.

To all whom it may concern:

Be it known that I, LEONARD L. BASSETT, a citizen of the United States, residing at Sioux Falls, in the county of Minnehaha and 5 State of South Dakota, have invented certain new and useful Improvements in Wheel Pullers; and I do declare the following to be a full, clear, and exact description of the invention, such as will enable others skilled 10 in the art to which it appertains, to make and use the same.

My invention relates to improvements in tools for pulling gear wheels and other wheels from shafts and it is the principal 15 object of this invention to provide a tool of this character in which the pull hooks may be adjusted with respect to the cross arm of the tool, to a great number of positions, thus adapting the device for use in 20 connection with gear wheels and the like of numerous sizes, novel provision being made for holding the cross arm and pull hooks in their relatively adjusted positions.

A further object of the invention is to 25 provide a novel arrangement of adjustable braces for the pull hooks, which will prevent accidental slippage thereof from the work.

With the foregoing in view, the invention 30 resides in the novel subject matter herein-after described and claimed, the description being supplemented by the accompanying drawings.

Figure 1 is a side elevation of a tool constructed in accordance with my invention.

Figure 2 is a horizontal section on line 2-2 of Fig. 1.

Figure 3 is a view similar to Fig. 1 but illustrating the pull hooks and braces reversed.

In the drawing above briefly described, the numeral 1 designates a suitably shaped cross arm whose center is provided with a screw 2 or other shaft-engaging thrust device. Each end portion of the cross arm 1 is formed with a longitudinal slot 3 which preferably extends from the end of the arm to a point adjacent the thrust device 2. A pair of pull hooks 4 pass through the slots 50 3 and are located in a plane common to the axis of the thrust device 2, the shanks of the hooks 4 being formed with longitudinally spaced openings 5 for registration with any of a plurality of transverse openings 6 with 55 which the cross arm 1 is provided. Pins 7 are insertable through the registering open-

ings to pivotally connect the hooks 4 with the cross head 1 and by novel means described below, these pins are held removably in place.

Longitudinally adjustable diagonal braces 8 are provided between the hooks 4 and the cross arm 1, said braces being suitably pivoted to the hooks as indicated at 9 by means of appropriate removable pins which are necessarily removed when adjusting the hooks 4 longitudinally, said pins 9 being insertable through any of the openings 5. The ends of the braces 8 remote from the pins 9, are formed with openings 10 for registration with any of the openings 6, as occasion may require, and headed pins 11 are insertable through the registering openings as shown.

The braces 8 are preferably in the form of turnbuckles, consisting of three screw-threaded sections as shown and it will be seen that when they are longitudinally adjusted to the proper extent, they will hold the hooks 4 engaged with diametrically opposite portions of a wheel or the like, whether the hooks be in the position shown in Fig. 1 or be reversed as illustrated in Fig. 3. The portions of the hooks 4 adjacent their bills 12, are preferably beveled as indicated at 13, in order that they may be readily received between gear teeth.

For the purpose of holding the pins 7 and 11 in place and permitting removal thereof whenever desired, I provide a pair of retaining arms 14 which are pivoted at 15 to the intermediate portion of the cross arm 1, the pivotal axes being parallel with the axes of the openings 6. These arms are preferably formed of spring metal and they normally abut the heads of the pins 7 and 11 to hold the latter in place, as will be clear from the drawings. However, the arms may be swung to an inoperative position as illustrated in dotted lines in Fig. 1, thus permitting the pins to be removed when making any desired adjustment of the tool.

From the foregoing, taken in connection with the accompanying drawing, it will be seen that an extremely simple and inexpensive tool has been provided which will have an exceptionally wide range of adjustment and will be highly efficient and reliable. Excellent results have been obtained from the details disclosed and these details are therefore preferably followed. However, within the scope of the invention as claimed, 110 numerous changes may be made.

I claim:

1. A wheel puller comprising a cross arm having a central shaft engaging thrust device, a pair of pull hooks pivoted to the end portions of said cross arm and longitudinally and laterally adjustable thereon and braces having a pivotal and adjustable connection at one end with said cross arm and at their opposite ends with said pull hooks, said braces being formed in adjustably connected sections.

2. A wheel puller comprising a cross arm having a central shaft-engaging thrust device, and provided with spaced openings in its end portions, pull hooks having openings to register with any of the aforesaid openings, pins insertible through the registering openings and having heads to limit their insertion, and a pair of retaining arms pivoted to said cross arms and movable into contact with the heads of said pins to prevent accidental removal thereof, said retaining arms being sufficiently long to extend over all of the openings of the cross arm to engage the pins regardless of the openings in which they are located.

3. A structure as specified in claim 2, to-

gether with oblique braces for said hooks having openings to register with certain of the openings of said cross arm, and additional headed pins for passage through these registering openings, said additional pins also being held by said retaining arms.

4. A wheel puller comprising a cross arm having a longitudinal slot in each end and a plurality of longitudinally spaced openings transverse to said slots, the center of said cross arm being provided with a shaft engaging thrust device, a pair of pull hooks having portions received movably in said slots, longitudinally adjustable braces for said hooks having portions received movably in said slots, said hooks and braces having openings for registration with certain openings of said cross arm, headed pins for passage through the registering openings, and a pair of retaining arms pivoted to said cross arm and movable into abutting relation with the heads of said pins to retain the latter in place.

In testimony whereof I have hereunto affixed my signature.

LEONARD L. BASSETT.
